UNITED STATES PATENT OFFICE.

ROBERT GORTON, OF BROOKLINE, MASSACHUSETTS.

METHOD OF MAKING GARTERS.

1,325,716.

Specification of Letters Patent. Patented Dec. 23, 1919.

Application filed December 16, 1918. Serial No. 267,052.

To all whom it may concern:

Be it known that I, ROBERT GORTON, a citizen of the United States, residing at Brookline, in the county of Norfolk and State of Massachusetts, have invented certain new and useful Improvements in Methods of Making Garters, of which the following is a specification.

This invention relates to the manufacture 10 of gentlemen's garters of the class in which the stocking-engaging members are connected with the ends of the leg-band by clasp-suspending devices secured to a pad arranged between the ends of the leg-band.

15 This kind of garter is usually made of several pieces of different kinds of material. Usually the body of the pad is made of material which is faced and lined, and sometimes provided with an interlining. The 20 pad has usually been given triangular shape, resulting in considerable waste of material. The leg-band, in this class of garters, has always, so far as my knowledge extends, been made of separate material, its ends being 25 secured to the pad in various ways. I have found that a pad garter, of the general kind above specified, may be made without waste from a single piece of material and yet have all the characteristics and advantages of a 30 pad garter of usual construction except that the pad is somewhat smaller than that usually found in garters of this class, the size of the pad, however, depending upon the width of the strip of material employed.

35 In my application for Patent No. 267,053 I have shown, described and claimed a garter having the characteristics of the garter hereinafter described. I claim herein a novel method of making such a garter and 40 in practising such method I preferably proceed as follows:

A strip of suitable material is first folded upon itself and the two folds are secured together near the doubled or looped end of 45 the strip by a line of stitches which is preferably disposed diagonally across the strip. The looped end and the projecting portions are then flattened in such manner as to produce a pad having portions of the strip projecting upwardly from its upper part to 50 form a leg-band or portions thereof.

The clasp-suspending devices are then attached to the pad and the leg-band is equipped with the usual slide and fastening

device or cast-off. Obviously, however, the 55 strip or tape may be equipped with such devices before the pad is formed.

In the accompanying drawings:

Figure 1 is a perspective view of a garter embodying my improvements.

Fig. 2 shows a strip of material from which the pad and leg-band or portions thereof may be formed.

Fig. 3 shows the first step of the method which consists in doubling the strip upon 65 itself and securing the folded strip by a diagonal line of stitches.

Fig. 4 shows the next step where a wide loop is produced in the folded strip.

Fig. 5 shows how this loop is flattened.

Fig. 6 shows how the leg-band portions of the strip are flattened or bent in rear of the pad portion.

Fig. 7 is a front view of the blank in the position it assumes when bent in the manner 75 indicated in Fig. 6.

Fig. 8 indicates the next step where the clasp-suspending devices are associated with the pad.

Fig. 9 illustrates how the members are secured by properly arranged lines of stitches.

In Fig. 1 A indicates the pad, B the leg-band, and C, the usual tab which may be considered a part of the leg-band. D indicates a clasp with stocking-engaging members of well known construction and E, the suspending devices therefor which are attached to the pad. F indicates the usual slide or takeup and G indicates the fastening device or cast-off.

In the form of my invention shown in the drawings, the entire pad is formed of folded portions of a strip of the same material as the leg-band or portions of the leg-band, and the material is so folded as to 95 give body, stiffness and strength to the pad. The rear portion of the front of the pad is entirely covered by the material except at a small part of the bottom thereof as indicated at x. Other characteristics of the pad 100 are more fully set forth in my companion application for patent above mentioned.

Fig. 2 shows a piece of suitable material, in the form of a strip, from which the leg-band or portions of the leg-band are formed.

Fig. 3 shows the first step in the method which consists in folding the strip upon itself to produce a loop 1 and then securing

the two members of the folded strip together by a diagonal line of stitches as indicated at 2.

Fig. 4 shows the looped portion of the strip opened up and then this member of the strip is flattened as indicated in Fig. 5, to provide a pad part 3 and leg-band portions 4 and 5, these latter members being then flattened or bent around the rear portion of the 10 pad as indicated in Fig. 6. In this way a construction of the kind shown in Fig. 7 is produced.

The clasp may then be associated with the pad in the manner indicated in Fig. 8, the 15 clasp-suspending devices being inserted between the folds of the pad in rear of the front portion thereof. After this the parts are secured together by lines of stitches as indicated at y in Fig. 9. The cast-off and 20 slide may then be applied to the leg-band, or as before stated these parts may be attached to the leg-band before the folding operation takes place.

There is a distinct advantage in stitching 25 together upon a diagonal line the looped portion of the strip of material. By this simple operation, which is quickly and inexpensively executed, the formation of the pad and the upwardly extending leg-band 30 portions is definitely and entirely determined and the leg-band portions are firmly secured to the pad portion of the strip along the line which will become the center of the pad. By thereafter simply flattening or 35 bending the looped portion and projecting ends of the strip the pad and the leg-band portions are completely formed and now only require to be secured in flattened position. For these reasons this stitching step 40 is a highly advantageous one and is employed in the preferred way of practising my invention. This step is however not absolutely essential to a practice of my invention, broadly considered, which, in one 45 of its aspects, may be described as forming the pad and leg-band portions from a strip of material by making four diagonal folds of the strip, *i. e.*, two oppositely inclined diagonal folds where the leg-band 50 portions join the pad and two oppositely inclined diagonal folds where the front layer of the pad joins the back portion thereof. Obviously these diagonal folds may be determined and made in other ways than in 55 the preferred manner herein set forth and without stitching together a looped portion of the strip.

While I do not consider it necessary to employ a lining or interlining for the pad 60 nor to apply a facing to the pad, as is usual in the manufacture of pad garters, such linings and facings may be added if desired.

The material employed may be of many 65 different kinds but preferably I use a tubular or double-sided strip of material in

order to obtain a better finish and to facilitate in connecting parts of the leg-band.

The drawings illustrate a garter where the parts are made from strip material of the same or uniform width throughout but 70 this is not essential so far, at least, as some features of my invention are concerned.

Obviously a garter made in accordance with my invention may be produced more 75 cheaply and more quickly than heretofore and without the waste of material incident to the manufacture of other garters of this class, and yet a garter as thus produced is light, neat and well fitting and is also comfortable, strong and durable. 80

I claim as my invention:—

1. The method of making portions of a garter, which consists in folding a strip of suitable material upon itself, securing together the two folds of the strip near one 85 end to form a looped portion, flattening said looped portion and the projecting ends of the strip to form a pad and leg-band parts, securing the parts in flattened position and securing to the pad a suitable clasp. 90

2. The method of making portions of a garter, which consists in bending a strip of suitable material to form a looped portion, securing the folds of the strip thus bent near its looped end, flattening the looped 95 portion and the projecting ends of the strip to produce a pad and leg-band parts, associating a clasp with the pad, and stitching the pad to secure the folded parts together and to fasten the clasp thereto. 100

3. The method of making portions of a garter, which consists in folding a strip of suitable material upon itself, securing together the two folds of the strip near one end by a diagonal line of stitches to form a 105 looped portion of the strip, bending and flattening the end of said strip and said looped portion to form a pad with portions of the leg-band extending therefrom, associating a clasp with the pad, and then securing together the folded portions of the 110 pad, the leg-band and the clasp to complete the garter.

4. The method of making portions of a garter, which consists in first connecting two 115 layers of strip material by a diagonal line of stitches, then folding each layer upon itself along the line of stitches and away from the other layer to form pad parts with integral leg-band parts. 120

5. The method of making portions of a garter which consists in first connecting two layers of strip material by a diagonal line of stitches, then folding the material to form a pad with integral leg-band portions, 125 and then securing the folded portions of the pad and the leg-band to each other by suitably arranged lines of stitches.

6. The method of making portions of a garter, which comprises making from a strip 130

of material a pad with integral leg-band portions extending oppositely therefrom by folding said strip upon itself upon two oppositely inclined diagonal lines to form the 5 leg-band portions and upon two other oppositely inclined diagonal lines to form the pad and securing the parts in their folded relation.

7. In the method of making from a strip 10 of material parts of a garter having a pad with integral leg-band portions extending oppositely and at an angle therefrom, those steps which consist in folding the strip upon itself upon two oppositely inclined diagonal 15 lines to bring the two layers of each fold in contact with each other and thereafter stitching the two layers of each fold to a third layer of the strip material joining the two folded parts.

20 8. In the method of making from strip

material portions of a garter having a pad with leg-band parts extending oppositely therefrom, those steps which consist of superimposing one layer of the material directly upon another layer thereof, then 25 stitching the two portions together upon a diagonal line and then forming pad and leg-band portions from the material thus connected.

9. In the method of making from a strip 30 of material portions of a garter having a pad with integral leg-band portions extending oppositely therefrom, that step which consists in stitching together upon a diagonal line a looped portion of said strip 35 previous to its being folded into pad form.

In testimony whereof, I have hereunto subscribed my name.

ROBERT GORTON.
